UNITED STATES PATENT OFFICE.

NATHANIEL BALDWIN, OF MILL CREEK, UTAH.

TELEPHONE-RECEIVER.

1,153,593.

Specification of Letters Patent. Patented Sept. 14, 1915.

Application filed March 27, 1913. Serial No. 757,220.

To all whom it may concern:

Be it known that I, NATHANIEL BALDWIN, a citizen of the United States, residing at Mill Creek, in the county of Salt Lake and 5 State of Utah, have invented new and useful Improvements in Telephone-receivers, of which the following is a full, clear, and exact description.

The present invention appertains to telephone receivers, and is particularly an improvement over my former Patent No. 957,403, issued May 10, 1910.

It is the object of the present invention to provide a very compact and effective arrangement of the working parts.

The invention is illustrated in the accompanying drawing, wherein: Figure 1 is a metrical section through a watch case form of receiver. Fig. 2 is a similar section of 20 another form of receiver, portions being shown in elevation. Fig. 3 is a cross section taken on line A—B of Fig. 1. Fig. 4 is a sectional detail taken on the line C—D of Fig. 3.

Each form of the invention embodies a shell or casing 1 of circular outline, which has the rim of a cup 2 seated against its edge. Disposed within the shell 1, is a circular permanent magnet 5 divided at one side to 25 provide spaced poles located at the opposite sides of the median plane of the magnet 5. U-shaped pole pieces 3 and 4 each has one of its limbs resting directly against and secured to one pole of said magnet, by means 30 of screw or securing element 6. The limbs of the pole pieces 3 and 4 project toward one another beyond the poles of the permanent magnet, and an electromagnet is secured between the pole pieces. This electromagnet 40 embodies a flattened tube 7 having its sides approximately flush with the ends of the pole pieces 3 and 4, and provided with flanges or heads 8 at its ends resting against the limbs of the pole pieces. The electromagnet 45 embodies a coil wound around the tube or spool 7, as will be apparent, and as is well understood. An armature 9 is fulcrumed within the tube or electromagnet 7 by means of the wires or pins 10 carried by the tube 7.

Blocks 11 are secured between the pole pieces 3 and 4 to properly space them, and to assist in holding the tube or spool 7 in position.

50 A diaphragm 12 is clamped against the rim of the cup 2, by means of a cap or ear piece

13 threaded upon the rim of the shell 1, said diaphragm being parallel with the median plane of the permanent magnet 5.

The pole pieces 3 and 4 project inwardly 60 within the permanent magnet, and the armature 9 is disposed radially of the permanent magnet, a link 14 connecting the inner end of the armature 9 and the central portion of the diaphragm. The diaphragm 12 is 65 provided with a washer 15 at its center through which the link 14 is engaged, to prevent the breakage of the diaphragm or the loosening of the link 14 therefrom.

A doubled spring 16 has one end engaged 70 to the outer end of the armature 9, and has its other end engaged to the projecting end of that limb of the pole piece 4 which is secured to the respective pole of the permanent magnet, so that the spring 16 projects between the poles of the permanent magnet. By the arrangement of the permanent magnet, pole pieces, armature, spring and associate parts, a compact arrangement is provided, especially due to the 75 positioning of the pole pieces and spring relative to the permanent magnet as illustrated and described.

A binding post 17 is carried by the cup 2 remote from the poles of the permanent 80 magnet, and is clamped thereto by means of a nut 18 threaded upon the binding post. Insulating washers 19 are carried by the post 17, and an insulating sleeve 20 is mounted upon the post between the washers 90 19. Terminal elements 21 are engaged to the sleeve 20 and are connected to the terminals of the coil of the electromagnet. The terminals 22 of the conductors are engaged to the sleeve 20 to be in electrical 95 connection with the respective terminal elements 21. A nut 23 is threaded upon the post 17 for clamping the other elements thereon.

I claim:

100 A telephone receiver embodying a circular permanent magnet divided at one side to provide spaced poles located at the opposite sides of the median plane of the said magnet, U-shaped pole pieces each having one 105 of its limbs resting directly against and secured to one pole of said magnet, the limbs of the pole pieces projecting toward one another beyond the poles of said magnet, an electromagnet secured between the pole pieces, a diaphragm parallel with said median plane of the permanent magnet, the 110

ole pieces projecting inwardly within said permanent magnet, an armature fulcrumed within the electromagnet and disposed radially of the permanent magnet, a link connecting the inner end of the armature and the diaphragm, and a doubled spring having its ends engaged to the other end of the armature and the projecting end of that limb of one pole piece which rests against and is secured to the respective pole of the

permanent magnet, the spring projecting between the poles of the permanent magnet, whereby the positioning of the pole pieces and spring relative to the permanent magnet provide a compact arrangement.

NATHANIEL BALDWIN.
